MICHAEL BECK, OF MINNEAPOLIS, MINNESOTA.

VAPORIZER AND PREHEATER FOR INTERNAL-COMBUSTION ENGINES.

Application filed November 28, 1921. Serial No. 518,183.

My invention relates to improvements in internal combustion engines and more specifically to vaporizers and preheaters for heavy hydrocarbon oils to be used as fuel for such engines, and has for its object to improve the same in the several particulars hereinafter noted.

To the above end, generally stated, the invention consists of the novel devices and combinations of devices hereinafter described and defined in the claims.

In the accompanying drawings, which illustrates the invention, like characters indicate like parts throughout the several views.

Referring to the drawings:

Fig. 1 is a view partly in diagram and partly in longitudinal central section of an automobile chassis having mounted thereon an internal combustion engine to which the invention is applied:

Fig. 2 is a view principally in central vertical section taken through the cylinder head of the engine on an enlarged scale;

Fig. 3 is a fragmentary detail view of the water supply tank and vapor and water pipe attached thereto;

Fig. 4 is an enlarged fragmentary view, partly in side elevation and partly in central longitudinal section, showing the exhaust pipe and vaporizer and pre-heater;

Fig. 5 is a fragmentary view in section taken on the line 4—4 of Fig. 4;

Fig. 6 is a view in section taken on the line 6—6 of Fig. 5;

Fig. 7 is a view partly in elevation and partly in diagram showing the heating element and electric circuit therefor; and

Fig. 8 is a fragmentary detail view of the heating element.

The numeral 9 indicates the chassis of an automobile and an internal combustion engine mounted thereon is indicated as an entirety by the numeral 10, with the exception of the cylinders 11, carbureter 12, intake manifold 13, exhaust manifold 14, exhaust pipe 15 and muffler 16. A fuel supply or oil tank for the internal combustion engine 11 is indicated by the numeral 17.

The invention includes a cylindrical casting 18, axially located within the exhaust pipe 15, and has its lower end closed by a base 19 screwed therein and its upper end is closed by a cap 20 also screwed therein.

Said cap 20, outward of the casing 18, is provided with upwardly converging side walls which terminate in an externally screw-threaded end 21 to which is applied an elbow 22 connected by a pipe 23 to the carbureter 12 and which pipe 23 extends centrally through an aperture in the exhaust pipe 15. The cap 20 affords a chamber 24 and on the under side of the base 19 is a depending axially located air chamber 25, in the lower end of which is screwed one end of the transverse portion of a T-coupling 26 and the other end of said transverse portion of said coupling is closed by a cap 27 having an aperture 28. The perpendicular portion of the T-coupling 26 is connected to the fuel supply tank 17 by a pipe 29.

In the lower portion of the cap 20 is a head 30, which forms the bottom of the chamber 24 and is provided with a central depression 31. A valve seat 32 is formed in the head 30 at the upper edge of the depression 31 for an intake valve 33 arranged to open under the suction stroke of the engine 10. This valve 33 is provided with a depending stem 34 which is guided in a seat 35 in the head 30 and has, on its lower end, a needle valve 36.

Within the casing 18 are concentric cylindrical shells 37, 38 and 39 axially located in said casing and dividing the same into an oil chamber 40, an air chamber 41 and inner and outer mixing chambers 42 and 43, respectively, and which chambers 41, 42 and 43 progressively increase in area. The shells 37, 38 and 39 are held in position by annular shoulders on the base 19 and head 30.

In the lower end of the air chamber 25 are circumferentially spaced ports 44, which open to the atmosphere, and in the upper end of said chamber are circumferentially spaced ports 45, which open into the lower end of the chamber 41. Circumferentially spaced ports 46, in the upper end of the shell 38, afford communication between the air chamber 41 and inner chambers 42, and circumferentially spaced ports 47 in the lower end of the shell 39 afford communication between the inner chamber 42 and the outer chamber 43. In the upper end of the shell 39 and wall of the depression 31 are aligned circumferentially spaced ports

48 which afford communication between the outer chamber 43 and said depression under the intake valve 33.

The shell 40 is made up of two axially spaced sections connected by an internal plug 49 having screw-threaded engagement therewith and provided with a passageway 50 normally closed by the needle valve 36. This plug 49 separates from the oil chamber 40 an upper oil chamber 51 and the passageway 50 forms a restricted opening, which affords communication between the oil chambers 40 and 51. Circumferentially spaced ports 52, in the upper end of the shell 37, afford communication between the upper oil chamber 51 and the air chamber 41.

Within the oil chamber 40 is a heating element 53 which, as shown, is in the form of a very fine closely coiled wire spirally wound around a tapered holder 54 formed on the lower end of the plug 49. One end of the heating element is ground on the plug 49 and the other end thereof is attached to a wire 55 in the ignition and lighting system 56 for the vehicle to which the invention is applied. Preferably, the wire 55 will be connected to the dimmer circuit of the system as the same is generally little used. An insulation of mica 57 or other suitable material is interposed between the heating element 53 and the holder 54. The wire 55 extends axially from the heating element 53 through the shell 37, coupling 26 and aperture 28 in the cap 27 and is held out of contact therewith by a piece of cork 58 or other suitable insulating material held in the lower end of said coupling 26 by the cap 27 and through which cork said wire is inserted.

The intake valve 33 is yieldingly held closed by a relatively light coiled spring 59 which encircles the valve stem 34 and is compressed between the under side of the head 30 and an annular flange 60 on said valve stem. This spring 59 is applied to the valve stem 34 by inserting the same over the needle valve 36 and past the flange 60 by turning the same on said flange with a screw action. The flange 60 is of a diameter not larger than the valve stem 34, so that when the spring 59 is removed therefrom, said valve stem may be inserted through the seat 35 or removed therefrom.

By unscrewing the base 19 from the casing 18, the shells 37, 38 and 39 may be removed from said casing, and when removed, the spring 59 may be applied to the valve stem 34 or removed therefrom.

The valves 33 and 36 seat simultaneously and, to adjust the screw plug 49 to the needle valve 36, the lower portion of the shell 37 may be removed from said screw plug, the upper portion of said shell held in position against the head 30 and the plug

49 screwed either into or out of the upper portion of the shell, as the case may require.

The operation of the invention thus far described may be briefly described as follows:

Heavy hydrocarbon fuel, such as distillate kerosene and the like, in the supply tank 17 will flow through the pipe 29, under the action of gravity, and fill the chamber 40 up to the plug 49 so that the heating element 53 will be completely immersed therein. The switch 55' for the dimmer or other circuit in which the heating element 53 is included is then closed to close the respective circuit and heat the oil in which said element is emersed and thereby start vaporization. The engine 10 is then started in the customary manner and, under the suction stroke thereof, the valves 33 and 36 will be opened and the hydrocarbon vapor in the oil chamber 40 will be drawn through the passageway 50, around the open needle valve 36, into the upper oil chamber 51 and through the ports 52 where it will commingle with air which, under the suction stroke of the engine, is drawn into the air chamber 41 through the ports 44 and 45 and the air chamber 25. Said hydrocarbon vapor and air will be further drawn downward through the inner chamber 42, through the ports 47, and into the outer chamber 43, where it will enter the depression 31 through the ports 48.

From the depression 31, the commingled hydrocarbon vapor and air will be drawn into the chamber 24, around the open valve 33 and conveyed therefrom through the pipe 22 to the carburetor 12, where a further air supply will be commingled therewith.

After the engine has been running a short time, the hot exhaust gases passing through the exhaust pipe 15 will come in contact with the casing 18 on all sides thereof and very quickly heat the same together with all parts carried thereby. During the travel of the hydrocarbon vapor and air, as indicated by the arrows in Fig. 5, vaporization will continuously take place, due to the heat produced by the hot exhaust gases passing over the casing 18, and the expansion of the fuel is permitted by the progressively increased size of the several chambers in said casing. The switch 55' may be operated to cut out the heating element 53 as soon as the heat from the exhaust starts vaporization.

At the time the vapor fuel leaves the casing 18, moist steam is commingled therewith. This steam is produced by conveying water from a supply tank 61 through a pipe 62 to a heating coil 63, the receiving end portion of which encircles the casing 18 within the exhaust pipe 15. The delivery portion of the heating coil 63 is extended from the casing 18 longitudinally within the exhaust manifold 14, then folded upon itself, extend-

ed axially through its coil and tapped into the elbow 22. Water passing through the heating coil 63 is very quickly heated and converted into steam. The water tank 61 is suspended from the rear end of the chassis 9 and the receiving end of the pipe 62 is closely positioned over the bottom of said tank.

Water from the pipe 62 is introduced into the heating coil 63 by an atomizer, which includes a nozzle 64 on the discharge end of the pipe 62 and closely and axially positioned in respect to the receiving end of the heating coil 63 outward of the exhaust pipe 15. Surrounding the nozzle 64 is a casing 65, one end of which is screwed onto the receiving end of the heating coil 63 and the other end of which is screwed onto a pressure pipe 66 which leads to the tank 61 at the top thereof, and through which pipe 66 the pipe 62 axially extends.

To produce a partial vacuum in the casing 65 at the nozzle 64 and thereby produce a suction to draw water from the tank 61 and spray the same into the heating coil 63 and at the same time produce pressure on the body of water in said tank to force the same therefrom into the pipe 62 and to the nozzle 64, I provide a novel device which acts automatically with a pump action. This device includes tapping into one or more of the engine cylinders 11 an upright valve casing 67 having a T-head 68. Each valve casing 67 has communication with the respective engine cylinder 11 through a port 69, at the upper end of which is a valve seat 70 on which rests a relatively small gravity held check ball valve 71 and normally closing said port. Normally open ports 72 connect the valve casing 67 with their T-heads 68 and at the lower ends of which ports are valve seats 73 adapted to receive relatively large check ball valves 74 for closing the ports 72. The balls 74 closely engage the walls of the valve casings 67, so that there is very little leakage therearound and said balls normally rest on the balls 71.

A pipe 75, having an expansion chamber 76 interposed therein, connects the T-heads 68 to the casing 77 of a needle valve 78 and a pipe 79 connects the valve casing 77 to the casing 65 of the atomizer and opens therein, just back of the nozzle 64. On the valve casing 77 is a valve-equipped priming cup 80, which has communication with the pipe 75, when the needle valve 78 is closed, through a by-pass 81 in the valve casing 77.

The action of the atomizer, in introducing steam into the fuel for the engine to increase the efficiency thereof, is as follows:

During compression in the cylinders 11, the balls 71 will be lifted from their seats 70 to open the ports 69, and the balls 74 will be lifted into their seats 73 and close the ports 72 and thereby prevent leakage

from the cylinders 11. By making the balls 74 of such size as to closely engage the walls of the casing 67, the same will be carried into their seats 73, during compression, before any of the fuel mixture can escape there- 70 around.

During the suction stroke in the cylinders 11, the balls 71 will drop into their seats 70, close the ports 69 and trap the fuel mixture in the casing 67. The balls 74 then drop 75 away from their seats 73 and the trapped fuel charge escapes around said balls and enters the pipe 75 where it will pass the needle valve 78 and enter the pipe 79, which will convey the same to the nozzle 64 and there- 80 by create a partial vacuum in the casing 65. As previously stated, this partial vacuum will draw the water from the tank and spray the same into the heating coil 63. A portion of the fuel charge will also enter the 85 tank 61 through the pipe 66 and create a pressure on the water therein to assist in carrying the same to the nozzle 64. By adjusting the needle valve 78, the amount of fuel charge passing from the pipe 75 to the 90 nozzle 64 may be controlled.

If it is necessary to prime the engine, the needle valve 78 may be closed and the gasoline or other priming fluid poured into the cup 80 when its valve is open. This fluid 95 will enter the pipe 75 through the by-pass 81 and be conveyed to the several cylinders of the engine. In cranking the engine, the compression will move the balls 71 away from their seats 70 and thereby permit the 100 charging fluid to enter the cylinders.

What I claim is:

1. The combination with an internal combustion engine, of a casing arranged to be heated by the exhaust from the engine, oil, 105 air and mixing chambers in the casing, said oil and air chambers having communication with the mixing chamber, said mixing chamber having communication with the intake of the engine, an intake valve normally closing the mixing chamber to said intake and arranged to be opened under the suction stroke of the engine, a valve actuated by the intake valve for controlling the oil supply 110 from its chamber to the mixing chamber, and a heating element immersed in the oil in the oil chamber.

2. The combination with an internal combustion engine, of a casing arranged to be heated by the exhaust from the engine, oil, 120 air and mixing chambers in the casing, said oil and air chambers having communication with the mixing chamber, said mixing chamber having communication with the intake of the engine, an intake valve normally closing the mixing chamber to said intake and arranged to be opened under the suction stroke of the engine, a valve actuated by the intake valve for controlling the oil supply 125 from its chamber to the mixing chamber, 130

and an electric heating element immersed in the oil in the oil chamber.

3. The combination with an internal combustion engine, of a casing arranged to be heated by the exhaust from the engine, an oil chamber in the casing, an air chamber in the casing surrounding the oil chamber, a mixing chamber in the casing surrounding the air chamber and having communication with the intake of the engine, said oil and air chambers having communication with the mixing chamber, an intake valve normally closing the mixing chamber to said intake and arranged to open under the suction stroke of the engine, and a valve for holding a body of oil in the oil chamber to be heated by the exhaust and actuated by the intake valve for controlling the oil supply from its chamber to the mixing chamber.

4. The combination with an internal combustion engine, of a casing arranged to be heated by the exhaust from the engine, an oil chamber in the casing, an air chamber in the casing surrounding the oil chamber, a return mixing chamber in the casing surrounding the air chamber and having communication with the intake of the engine, a partition in the oil chamber separating therefrom an upper oil chamber, said partition having a restricted passageway connecting the oil chamber with the upper oil chamber, said upper oil chamber and the air chamber having communication with the mixing chamber, an intake valve normally closing the mixing chamber to said intake and arranged to open under the suction stroke of the engine, and a valve normally closing said passageway and arranged to be actuated by the intake valve for controlling

the oil supply from the lower chamber to the upper oil chamber.

5. The combination with an internal combustion engine, of a cylindrical casing arranged to be heated by the exhaust from the engine, concentric shells in the casing affording a centrally located oil chamber, an air chamber outward of the oil chamber and inner and outer return mixing chambers outward of the air chamber and having communication with the intake of the engine, said oil and air chamber having communication with said mixing chambers, an intake valve normally closing the mixing chamber to said intake and arranged to open under the suction stroke of the engine, and a valve actuated by the intake valve for controlling the oil supply from its chamber to the mixing chamber.

6. The combination with an internal combustion engine, of a casing arranged to be heated by the exhaust from the engine, oil, air and mixing chambers in the casing, said oil and air chambers having communication with the mixing chamber, said mixing chamber having communication with the intake of the engine, a plug in the oil chamber having a restricted passageway leading to the mixing chamber, an intake valve normally closing the mixing chamber to said intake and arranged to be opened under suction stroke of the engine, a needle valve carried by the intake valve for controlling the oil supply from a chamber and normally closing said restricted passageway, said plug being adjustable toward and from the needle valve, and a heating element carried by said plug within the oil chamber.

In testimony whereof I affix my signature.
MICHAEL BECK.
